MACHINE OPERATING MECHANISM.

1,298,400.

Specification of Letters Patent. Patented Mar. 25, 1919.

Application filed July 6, 1918. Serial No. 243,680.

To all whom it may concern:

Be it known that I, LYNUS CLYDE REYNOLDS, a citizen of the United States, and resident of Washington, in the District of Columbia, have invented certain new and useful Improvements in Machine Operating Mechanisms, of which the following is a specification.

The present invention relates to a machine for punching or performing other work on cards or sheets of paper or other material, for example, such as are used for recording and tabulating census and other compilations, and it is the primary object of the invention to provide in combination with a machine for feeding sheets or other objects and manually controlled for punching or performing other work on the sheets, means whereby some of the work will be performed automatically, or without manual aid, according to a pattern or predetermined arrangement. In other words, the machine is a combination manual and automatic one, in order that some of the punches or work performed on the sheets can be done according to manual selection for the successive sheets, and in order that the holes punched in or other work performed on a series of successive sheets in the same manner or in repeated duplicate, will be accomplished automatically. Thus, the machine is operable for automatically punching or performing other work on each of the successive sheets to provide predetermined perforations or the like, when a series of sheets have the same data to be recorded thereon, while the rest of the perforations or other work performed on the sheets are accomplished under manual control and selection, so that they will differ on the various sheets as desired.

This machine is particularly designed for use in punching perforations or holes in cards, although the invention can be used in machines for performing other work on cards and sheets of various sorts. Card punching machines are now used quite extensively for tabulating census and other statistical data and compilations, and the cards when punched are used in connection with sorting and computing machines. The sorting machines will sort the cards according to certain holes punched therein, while the computing machines will add up the numbers or other data recorded on the cards

by the holes punched therein. It is the present practice to use two punching machines, viz., a gang punch and a selective punch. The gang punch is used for punching similar holes in a number or stack of cards, with a view to saving labor and time, when a series of cards all have corresponding holes or perforations, because this gang-punching will eliminate the individual punching of the cards excepting for those additional perforations or holes which vary for the successive cards. The gang-punched cards are then punched by the selective punches by manual selection according to data which varies for the different cards, and the gang-punching will therefore save some time in the selective punching.

It has been found in practice that the gang-punching of stacks of cards is objectionable for several reasons. Not infrequently, the work of selectively punching the cards is held up awaiting the gang-punching thereof, thereby losing time. Furthermore, in gang-punching, the punches must penetrate all of the cards in a stack which are being gang-punched, and in order to make the gang-punching profitable, it is necessary to punch quite a number of the cards at once. This results in the perforations or holes of the intermediate cards being imperfectly formed, and having ragged or feather edges, due to the fact that only the lowermost card or cards are firmly supported on the die, while those above, being superposed, can yield more or less as the cards are under compressive strain when the punches penetrate them. Thus, some of the stock instead of being sheared from the cards by the punches with a clean cut, is pushed down by the punches to form a feather edge, and this has caused trouble in the sorting of the cards, because these feather edges project from the sides of the cards and interfere with the sorting.

The purpose of this invention, in the art of card punching, is three-fold. First, it dispenses with the use of gang-punches altogether; secondly, it saves the time required for gang-punching by combining this operation with the selective punching automatically and without consuming additional time in selective punching; and third, it eliminates irregular punching or feather edges around the perforations or holes, be-

- cause the cards in being punched individually will have the perforations cut clean. The present machine, as used for punching cards, is operable manually in the usual 5 way for making the selective punches, while the duplicate or similar punching operations, now done by the gang-punching operation, is accomplished automatically between the intervals of hand punching. The 10 automatic mechanism of the machine is controlled by a pattern or master-card which is previously punched so as to have such perforations as are to be repeated for a series of cards, and the machine is so constructed that 15 when this pattern card is applied, the successive blank cards which are inserted and punched selectively under manual control, will be automatically punched during the intervals of manual punching, according to 20 the perforations in the pattern card, thereby combining the present method of gang-punching and selective punching into one operation with resultant decided advantages in overcoming the objections in the prevailing 25 practice.

This invention is not only useful in the art of punching or perforating sheets, but is also capable of advantageous use in other arts wherein sheets or other objects are 30 operated on by work-performing elements, some of the work being repeated for which the automatic mechanism forming the subject matter for the present invention is suited, while the remainder of the work is 35 done selectively under manual control.

Another object is the provision of an adjustable and reversible key-board for the machine, in order that it can be placed at different positions for the convenience of 40 the operator, and to enable the key-board to be reversed for both right and left hand control and operation. This feature is of advantage to relieve the operator, as the continued operation of these machines 45 throughout the day sometimes tires the operator, whereas if the key-board can be shifted to enable the operator to change his or her position, relief can be had. Furthermore, the reversal of the key-board enables either 50 the right or left hand to be used with equal facility.

With the foregoing and other objects in view, which will be apparent as the invention is more fully understood, the invention 55 resides in the combination of elements as hereinafter described and claimed, it being understood that various changes can be made within the scope of what is claimed, in adopting this invention to various uses, 60 within the spirit of the invention.

The invention is illustrated in the accompanying drawings, wherein—

Figure 1 is a plan view of the improved machine.

Fig. 2 is a longitudinal section on line

2—2 of Fig. 1, portions on the near side of the plane of section being shown.

Fig. 3 is a cross section on the line 3—3 of Fig. 2 showing the means for preventing more than one of the operating levers 70 being operated at a time.

Fig. 4 is a cross section on the line 4—4 of Fig. 2, and also showing the switch keyboard in section.

Fig. 5 is a diagrammatical view showing 75 the electrical circuits.

As illustrated in the drawings, the invention is embodied in a card punching machine, which comprises a suitable base or frame 11 having a guide or slide way 12 80 for the card 13 to be punched or perforated, and a ratchet bar or carrier 14 is slidable longitudinally in the base 11 for feeding the card 13 longitudinally as it is operated on or punched. The carrier 14 has upturned 85 portions 15 at its ends against which the ends of the card or sheet 13 bear, to cause said card to move with the carrier. This carrier is advanced by a spring motor device 16 or the like, and an escapement device 17 coöperates with the carrier so that it is advanced step by step, but permits the carrier to be slid rearwardly quickly to start the punching operation. The base 11 has a transverse die 18 over which the 90 card 13 moves, and a transverse row of punches or work performing members or plungers 19 are disposed above said die to operate downwardly on the card. The punches or plungers 19 are slidable vertically in guides 20, the lowermost one of which holds the card 13 on the die 18, so that the lower ends of the punches will properly penetrate the card. The punches or plungers are raised by the springs 21. 100

The foregoing construction is quite similar to the selective punching machines now used, and the punches are arranged in a transverse row to correspond with the columns or rows of digits on the card, so that 110 in each position or step of the card, any one of the punches can be operated for making a corresponding perforation or hole in the card.

The punches or work performing members 19 are operated or depressed by means of levers 22 fulcrumed on a shaft 23 supported by standards 24 rising from the base at the opposite sides of the guide 12, and the respective levers 22 rest on the punches 19 and are raised thereby. The operating levers 22 are actuated by solenoids, electromagnets or other suitable actuating means, and as shown, depending cores 25 are connected to the levers 22 and work within the 125 coils 26 of the solenoids. These solenoids are shown as being mounted on a shelf 27 bridging the guide 12 on the base. When any one solenoid is energized it will attract its core and thereby swing the correspond- 130

ing lever 22 downwardly and bring the corresponding punch into operation, and when the solenoid is deenergized, the parts are returned by the respective spring 21. The solenoids or electro-magnetic means are used in the present embodiment of the machine, but it will be understood that other suitable operating means can be used.

The means for preventing more than one of the levers 22 from being operated at a time, so as to avoid two or more punches being operated simultaneously, includes a transverse row of upstanding stops 30 below the levers 22 and between the vertical planes of oscillation of said levers. These stops 30 are supported for yielding movement transversely of the levers, and as shown, are supported by upstanding leaf springs 31 carried by a crossbar 32 above the guide 12. These springs 31 hold the stops 30 in position, so that any one lever 22 in being moved downwardly can pass between the two corresponding stops 30, and in doing so will separate said stops. The stops in contacting with each other will be moved in opposite directions from the lever 22 that is moved, and this will prevent any of the other levers 22 being moved, but when the actuated lever 22 returns to idle position, the stops 30 also return to normal position. As shown, an arch 33 carried by the base passes over the levers 22 to limit their upward movement and to also limit the separation of the stops 30.

A battery 34 or other source of electrical energy is used for energizing the solenoids 26, and a conductor or leader 35 connects one pole of the battery with one terminal of each of the solenoids. Individual conductors or leaders 36 are connected to the other terminals of the solenoids and extend to their respective contacts of key-operated switches 37 for the respective solenoids. The other contacts of said switches 37 are connected by a common conductor or leader 38 with the other pole of the battery 34. At any position of the card 13, it is an easy matter to operate the desired punch by simply closing the corresponding switch 37, which will close the circuit of the selected solenoid 26, and the corresponding punch is therefore brought into play, and as soon as the switch 37 is released, it opens the circuit and the solenoid being deenergized will permit the punch and its actuating means to return to normal idle position. By using the electro-magnetic operating means under the control of key-operated switches, the least possible manual effort is necessary to operate the punches, as the work is done electrically but under selective manual control.

In order to advance the card 13 whenever one of the punches has been operated and retrieved or returned, a lever 28 is fulcrumed

on the shaft 23 and extends under all of the levers 22 so as to be swung when any one of the levers 22 is operated, and the lever 28 is connected by a link 29 or other operative connection with the escapement 70 pawls 17. Thus, the escapement of the spring-actuated carrier 14 is operated when any one of the punches is operated, and this allows the carrier 14 and card 13 to advance one step for the next perforation immediately after one perforation is made.

Coming to the means for automatically causing the operation of the punches in certain positions or steps of the card 13, in the embodiment as shown, the base 11 has a shelf 39 supporting a slab 40 of insulating material and provided with a depression or receptacle 41 for receiving a pattern or master-card 42 having predetermined perforations or holes 42' punched therein in certain columns or rows which are to be repeated for a series of cards 13. This pattern card 42 is similar to the blank cards 13 and can be readily removed and replaced so that the automatic operation can be changed from time to time as required, or the automatic operation can be controlled by any other suitable pattern. Suitable means may be provided for holding the pattern card 42 in place, such as longitudinal lips or flanges 95 43 to overhang and over-lap the edges of the card. Longitudinal contact bars or strips 44 are embedded in the slab 40, so that the card 42 covers them, and in order that the perforations or holes 42' will expose the respective bars 44 which are arranged according to the digits or longitudinal rows of markings on the card. The bars 44 have binding posts 45 near one end of the slab 40 for the connection of the conductors 105 36, whereby to electrically connect the bars 44 with the respective solenoids or electromagnets, it being noted that the pattern card 42 is reversed in position relatively to the card 13, in view of the arrangement of the parts. The pattern card 42 being of paper or similar material will insulate the bars 44 from above, excepting where exposed through the perforations or holes 42'. These perforations 42' or equivalent means 110 are for the purpose of closing the circuits of the respective solenoids 26 at the different positions or steps of the card 13 determined by the longitudinal positions of the perforations in the pattern card. In order to 115 close these circuits through the perforations of the pattern card, there is provided a transverse rock shaft 46 journaled in bearings 47 carried by the forward portion 15 of the carrier 14, so that said shaft is movable with the card 13 relatively to the pattern card 42. This shaft 46 carries a contact comb or brush constituting spring fingers 48 extending downwardly and rearwardly to drag on the pattern card 42 dur- 130

ing the forward step by step movement of the card 13. There is one of the spring fingers 48 above each bar 44, and the lower free ends of said fingers have the same relative position on the pattern card 42 as the punches 19 have on the card 13, so that the fingers 48 serve as an indicator to enable the operator to readily observe from the card 42, the particular column of the card 13 that is under the punches. Furthermore, when the card 13 steps into a position to bring the fingers 48 over a column of the pattern card 42 having a perforation 42', the corresponding finger 48 will spring 15 downwardly through said perforation and make contact with the respective bar 44, so as to close the circuit of the respective solenoid. The shaft 46 has a finger piece 49 arranged to receive the pressure of the 20 thumb or finger for pushing the carrier 14 and card 13 which has been introduced, rearwardly to starting position, and this finger piece is so arranged that when it is pressed, it will turn the shaft 46 and raise 25 the contact fingers 48 off of the pattern card 42 during the rearward movement, thereby rendering the automatic circuit closing means inoperative during such rearward movement. A spring 50 between the finger 30 piece 49 and a part of the carrier 14 will turn the shaft 46 back to normal position as soon as the pressure against the finger piece 49 is relieved. Thus, when the carrier 14 and card 13 to be punched are slid rearwardly, the fingers 48 are raised off of the pattern card 42, and when the card 13 has reached its rearmost position to start its forward step by step movement, the fingers 48 will be returned against the pattern card 40 42 and brought under the desired tension thereagainst by the pressure of the spring 50.

The contact fingers 48 are connected by a common conductor or leader 51 with the conductor 38, whereby the bars 44 and their contact fingers 48 are connected in parallel with the corresponding switches 37, so that the circuit of any solenoid can be closed either by the corresponding switch 37 or the corresponding bar 44 and contact finger 48 according to whether the operation is controlled manually or automatically. In order to automatically break the circuit of the solenoids when they are automatically closed, and thereby automatically advance the card 55 13 and repeat the automatic operation if called for, a suitable switch 52 is disposed in the conductor 51 and means is provided for opening said normally closed switch 52 as soon as any of the punches 19 has completed its work in penetrating the card 13. As shown, the switch 52 is carried by one standard 24 and the lever 28 has an arm 53 so arranged that when the lever 28 is swung downwardly with any of the levers 22, the 60 arm 53 will contact with the switch 52 and

open it when the punch 19 that is operated has punched the card. This will immediately open the circuit of the energized solenoid, and the punch and lever 22 will therefore be returned promptly to normal position under the influence of the corresponding spring 21 and the escapement pawls will therefore allow the carrier 14 and card 13 to advance a step, just the same as they do as when the switches 37 are operated for operating the punches. 70 75

The switches 37 are embodied in an adjustable and reversible key-board comprising a casing 54 having a double clamp 55 for engaging the forward wall of the base or 80 frame 11 when said casing is inverted to either its reverse positions, and said clamp has a set screw 56 or other suitable means for fastening it to the base. This clamping means permits the casing 54 to be loosened 85 and shifted longitudinally along the base to any desired position for the convenience of the operator, or the casing 54 can be turned upside down for reversing the keys 58. The switches comprise companion contact springs 90 95 57 separated from one another and two sets of push buttons 58 are slidable through the opposite top and bottom walls of the casing and are arranged on opposite sides of the companion contact springs 57 whereby the push buttons or keys 58 on either side can be manipulated for moving the corresponding springs 57 against the opposite ones, thus rendering the key-board reversible. When one set of keys is uppermost, the same is suited for the right hand, whereas when the key-board is reversed or inverted, this will reverse the keys for left hand operation. The conductors 36 are connected to one spring 57 of each pair while the common conductor 38 105 is connected to the other springs so that when any one push button or key is pressed, this will close the circuit of the respective solenoid. The keys can be quickly manipulated with the slightest manual effort for operating the punches through the aid of the electro-magnetic means. 110 115

The operation of the machine is as follows: Supposing that the carrier 14 is in its foremost or card-receiving position, then a card 13 can be readily introduced by placing in the guide 12 between the portions 15. The operator then moves the carrier rearwardly by pushing on the finger piece 49, which will raise the contact fingers 48 off of the pattern card 42 during such rearward movement, and when the card 13 is moved to its rearmost position, the finger piece 49 is released and this lets the contact members 48 down on the pattern card 42. Now, if the first column of digits on the pattern card 42 has a perforation, then one of the fingers 48 will immediately make electrical contact through the perforation with the respective bar 44, and this will instantly energize the corresponding 120 125 130

solenoid and cause the punch operated thereby to punch the first hole in the card 13 automatically, and if, as illustrated, there are one or more successive columns on the card 42 having perforations, then, as soon as the first perforation is made and the switch 52 is opened so as to restore the operating means, the carrier 14 and card 13 will automatically advance one step, as well as the contact fingers 48. Therefore, the fingers 48 are removed from the first column and its perforation to the next column so that the respective finger 48 will spring down through the perforation of the latter column and repeat the automatic punching operation accordingly. This automatic operation is repeated until the fingers 48 reach a column on the pattern card 42 that is not perforated, when the card 13 comes to rest for manual operation. The automatic operation, even for several successive columns or positions, is accomplished rapidly, so as to lose no time, and will be done before the operator is ready to press a key 58. The selective manual punching is done by operating the keys 58, and whenever the fingers 48 reach a position on the card 42 having a perforation 42', then the automatic operation takes place instantly, and is repeated as required, so that the card 13 is ready for the next selective manual punching practically as quick as the operator is ready to press the next key 58. In this manner, as the card 13 moves step by step, the punching is done automatically in those positions of the card 13 determined by the perforations in the pattern card 42, while in the other positions of the card 13 it stops for manual-controlled punching, it being noted that as each perforation in the card 13 is completed by automatic or manual control, the card 13 advances one step and stops for manual control but only stops for an instant in automatic control while the automatic punching is completed and then steps on for the next operation. By changing the pattern card 42, the results of an adjustable gang-punching machine are quickly attained, and the present machine obtains the results of gang-punching without the objections incident thereto and with economy by dispensing with the gang-punching machines and attendant labor and time. In lieu of the gang-punching of the cards 13, according to the perforations 42', the present machine automatically provides the card 13 with corresponding perforations during the intervals of manually-controlled punching and without loss of time.

The term "sheets" in the appended claims is meant broadly for various blank objects or devices to be operated on in different ways, and furthermore, although the claims indicate that the sheet or object moves, same is to be taken in a broad sense as a relative motion of the parts, because the

same result would be obtained if the sheet or object stood still and the rest of the machine moved.

Having thus described the invention, what is claimed as new is:

1. A machine for operating on sheets, embodying means for feeding a sheet, manually-controlled work-performing members to operate on the sheet when fed from position to position, and means for automatically controlling said members at some previously selected positions only of the sheet to perform predetermined repetition work without manual aid and leaving the rest of the work for manual control in the other positions of the sheet. 70

2. A machine for operating on sheets, embodying means for feeding a sheet, work-performing members to operate on the sheet, keys controlling said members for manual operation, and means for automatically controlling said members at previously selected positions only of the sheet to perform predetermined repetition work without the aid of the keys and leaving the rest of the work 80 for manual control in the other positions of the sheet. 85

3. A machine for operating on sheets, embodying means for feeding a sheet step by step as work is performed thereon, manually-controlled work-performing members to operate on the sheet in each step, and means for automatically controlling said members in some previously selected steps only of the sheet to perform predetermined 90 repetition work without manual aid and leaving the rest of the work for manual control in the other steps of the sheet. 95

4. A machine for operating on sheets, embodying means for feeding a sheet step by step as work is performed thereon, work-performing members to operate on the sheet in each step, keys controlling said members for manual operation, and means for automatically controlling said members in previously selected steps only of the sheet to perform predetermined repetition work without the aid of the keys and leaving the rest of the work for key control in the other steps of the sheet. 105

5. A machine for operating on sheets, embodying means for feeding a sheet, work-performing members to operate on the sheet, manually-controlled operating means for said members, and means operable for 110 automatically controlling said operating means to automatically operate said members in some previously selected positions only of the sheet to perform predetermined repetition work without manual aid and leaving the rest of the work for manual control in the other positions of the sheet. 120

6. A machine for operating on sheets, embodying means for feeding a sheet, work-performing members to operate on the sheet, 130

- operating means for said members, keys controlling said operating means for manual operation, and means operable for automatically controlling said operating means in 5 previously selected positions only of the sheet to perform predetermined repetition work without the aid of the keys and leaving the rest of the work for key control in the other positions of the sheet.
- 10 7. A machine for operating on sheets, embodying means for automatically feeding a sheet step by step as work is performed thereon, work-performing members to operate on the sheet in each step, manually- 15 controlled operating means controlling said members, and means for automatically controlling the operating means in some previously selected steps only of the sheet to perform predetermined repetition work without 20 manual aid and leaving the rest of the work for manual control in the other steps of the sheet.
8. A machine for operating on sheets, embodying means for automatically feeding a 25 sheet step by step as work is performed thereon, work-performing members to operate on the sheet in each step, operating means for said members, keys controlling said operating means for manual operation, and 30 means operable for automatically controlling said operating means in previously selected steps only of the sheet to automatically operate said members for predetermined repetition work without the aid of the 35 keys and leaving the rest of the work for key control in the other steps of the sheet.
9. A machine for operating on sheets, embodying means for feeding a sheet, manually-controlled work-performing members to 40 operate on the sheet, a pattern for determining predetermined repetition work to be performed on the sheet in some positions only thereof and leaving the rest of the work for manual control, and means controlled by said 45 pattern and controlling said members to only operate them automatically in the predetermined positions of the sheet determined by said pattern.
10. A machine for operating on sheets, embodying means for automatically feeding a 50 sheet step by step as work is performed thereon, work-performing members to operate on the sheet in each step, keys controlling said members for manual operation, a pattern for determining predetermined repetition work to be performed on the sheet in some steps only thereof and leaving the rest of the work for key control, and means controlled by the pattern and controlling said 55 members in the predetermined steps only of the sheet determined by the pattern, to automatically operate said members without the aid of the keys.
- 60 11. A machine for operating on sheets, em-

bodying means for feeding a sheet, work-performing members to operate on the sheet, manually-controlled operating means for said members, a pattern for determining predetermined repetition work to be performed on the sheet in some positions only thereof and leaving the rest of the work for manual control, and means controlled by the pattern and controlling the operating means for automatically operating said members in the predetermined positions only of the sheet determined by the pattern, to perform the predetermined work without manual aid. 70

12. A machine for operating on sheets, embodying means for automatically feeding a sheet step by step as work is performed thereon, work-performing members to operate on the sheet in each step, operating means for said members, keys controlling the operating means for manual operation, a pattern for predetermined repetition work 85 to be performed on the sheet in some steps only thereof and leaving the rest of the work for key control, and means controlled by the pattern and controlling the operating means for automatically operating said members in 90 the predetermined steps only of the sheet determined by the pattern.

13. A machine for operating on sheets, embodying means for feeding a sheet, manually-controlled work-performing members to operate on the sheet, and means for automatically controlling said members to perform some of the work without manual aid for repetition, including a pattern having predetermined portions for controlling electrical 95 circuits in some positions of the sheet only and electrical means controlled by said portions to bring the members into automatic operation only in the predetermined positions of the sheet and leaving the rest of the 100 work for manual control.

14. A machine for operating on sheets, embodying means for feeding a sheet, manually-controlled work-performing members to operate on the sheet, a pattern sheet having 110 perforations for determining predetermined repetition work to be performed on the aforesaid sheet in some positions only thereof, and means operable through said perforations of the pattern sheet and controlling said members for automatically operating them in the predetermined positions only of the first mentioned sheet determined by the perforations in the pattern sheet and leaving the rest of the work for manual control. 115

15. A machine for operating on sheets, embodying means for feeding a sheet, manually-controlled work-performing members to operate on the sheet, a pattern sheet having 120 perforations to determine some of the work only to be performed on the aforesaid sheet for repetition, and electrical means co-operative with the pattern sheet and including 125

- circuits closed through said perforations to bring said members into automatic operation in some positions only of the first mentioned sheet determined by the perforations in the 5 pattern sheet and leaving the rest of the work for manual control.
16. A machine for operating on sheets, embodying means for automatically feeding a sheet step by step as work is performed 10 thereon, work-performing members to operate on the sheet, electrical means controlling the operation of said members, keys for manual control of said members, a pattern sheet having perforations to determine some of 15 the work only to be performed on the aforesaid sheet, and electrical circuit closing means operable through the perforations of the pattern sheet and controlling said electrical means to bring said members into operation automatically in some positions only 20 of the first mentioned sheet determined by the perforations in the pattern sheet and leaving the rest of the work for key control.
17. A machine for operating on sheets, embodying means for automatically feeding a sheet step by step as work is performed thereon, work-performing members to operate on the sheet in each step thereof, electrical operating means for said members, keys controlling 25 the operating means for manual operation, a pattern sheet having perforations to determine some of the work only to be performed on the aforesaid sheet, and circuit closing means operable through the perforations of the pattern sheet and controlling the operating means for the automatic operation of said members in predetermined steps 30 only of the first mentioned sheet determined by the perforations in the pattern sheet and leaving the rest of the work for key control.
18. A machine for performing work on sheets, embodying means movable back and forth for feeding a sheet in one direction, work-performing members to operate on the 35 sheet, and means including relatively movable coöperable parts, one movable with the sheet, for automatically controlling said members to operate on the sheet and means operable to prevent coöperation of said parts 40 when said movable part is moved in the other direction.
19. A machine for operating on sheets, embodying a carrier movable back and forth for feeding a sheet, means for feeding said carrier step by step in one direction, work-performing members to operate on the sheet, operating means for said members, a pattern for determining the work to be performed, 45 means coöperable with said pattern and controlling the operating means for the automatic operation of said members according to the pattern, the last named means and pattern being relatively movable, one with the carrier, and means for moving the car- 50 rier in the other direction to start the step 55 by step movement and to also prevent co-operation of the pattern and third named means during such movement of the carrier.
20. A machine for operating on sheets, embodying a carrier movable back and forth 70 for feeding a sheet, means for moving said carrier step by step in one direction, electrical operating means, work-performing members controlled by the operating means to operate on the sheet, a pattern sheet having 75 perforations to determine the work to be performed on the aforesaid sheet, circuit closing means coöperable with the sheet for closing circuits, through said perforations and controlling the operating means, said pattern and circuit closing means being relatively movable, one with the carrier, and means for moving the carrier in the other direction to start the step by step movement and operable to separate the pattern and 80 circuit closing means during such movement of the carrier.
21. A machine for operating on sheets, embodying means for feeding a sheet, work-performing members to operate on the sheet, 90 electrical operating means for said members, and a key board having switches controlling said operating means and a set of keys for operating the switches, said switch board being movable to different positions 95 relatively to the machine for the convenience of the operator.
22. A machine for operating on sheets, embodying means for feeding a sheet, work-performing members to operate on the sheet, 100 electrical operating means for said members, and a switch board having opposite right and left hand sets of keys and switches operated by the keys of both sets for controlling the operating means, said switch board being reversible for either right or left hand operation.
23. A machine for operating on sheets, embodying means for feeding a sheet, work-performing members to operate on the sheet, 110 electrical operating means for said members, a key board casing, opposite right and left hand sets of keys carried by said casing, a set of switches within the casing operated by the keys of both sets for controlling the operating means, and means for supporting said casing in various adjustments and in reverse positions for the operation of either set of keys in different positions.
24. A machine having a frame and work 120 producing members, and a key board having a set of keys operatively connected with said members, said key board being adjustably connected to said frame to permit the key board to be shifted to different positions 125 for the convenience of the operator.
25. A machine having work producing members, and a key board having reverse

sets of keys each connected to said members for either right or left hand operation.

26. A machine having work producing members, and a key board having opposite reverse sets of keys, means for reversibly supporting the key board to bring either set of keys into position for right or left hand operation, and means operated by the keys of both sets and controlling said members to operate them.

27. A machine having a frame and work producing means, and a key board having reverse sets of keys for the right and left hands of the operator, means operated by the keys of both sets for controlling the work producing means selectively, and means for supporting the key board relatively to said frame for bringing either set of keys into position for operation and for shifting the key board to different positions for the convenience of the operator.

28. A machine embodying means for feeding an object from position to position, manually operable work producing means to operate on the object in each position, and means operable automatically in certain previously selected positions only of the object, to perform predetermined work without manual aid and to leave the rest of the work for manual control and selection.

29. A machine embodying means movable back and forth for feeding an object from position to position, work producing devices to operate on the object in its different positions, and automatic means for controlling said devices, part of said automatic means being movable back and forth simultaneously with the first named means to bring the automatic means into operation.

30. A machine having means movable back and forth for feeding an object step by step, work producing devices to operate on the object in each step, and automatic means for controlling said devices, including a controlling pattern and coöperating

means movable relatively, one back and forth simultaneously with the first named means to bring the automatic means into operation.

31. A machine embodying means for feeding an object to different positions, manually operable work performing means to operate on the object in its different positions, and automatic means controlling said work performing means and controlled as the object is moved so that some previously determined work is taken up and performed automatically and the other work left for limited manual operation at desired points of the work before the automatic operation is again taken up.

32. A machine embodying means for feeding an object to different positions, work performing members to operate on the object in its different positions, and automatically operable means controlling said work performing means and constructed and arranged so as to be advanced by the movement of the feeding means and operative to start and perform previously selected work automatically and inoperative at previously determined points of the work to leave desired portions of the work for manual operation and selection.

33. A machine embodying means for feeding a sheet to different positions, work performing members to operate on the sheet in its different positions, operating means for said members, keys for manual control of said members, and means advanced by the movement of the feeding means controlling the operating means for automatically operating said members for previously determined work on the sheet and interrupting the automatic operation for a limited amount of work at desired points of the work at such points for key control.

In testimony whereof, I hereunto set my hand this 2nd day of July, 1918.

LYNUS CLYDE REYNOLDS.
